UNITED STATES PATENT OFFICE.

GUSTAVE A. DOSTAL, OF DALLAS, SOUTH DAKOTA.

LACING CUTTER.

Application filed February 2, 1926. Serial No. 85,564.

This invention relates to a device for cutting belt lacings and the like from strips or pieces of leather, the general object of the invention being to provide a member having 5 a slot therein through which a portion of the strip is pulled with the knife across the slot for cutting a strip from the piece to form the lacing.

Another object of the invention is to make 10 the knife adjustable for cutting different sizes of lacings and also to make the slot adjustable in width so that the device can be used on different thicknesses of leather.

This invention also consists in certain 15 other features of construction and in the combination and arrangement of the several parts, to be hereinafter fully described, illustrated in the accompanying drawings and specifically pointed out in the appended 20 claim.

In describing my invention in detail, reference will be had to the accompanying drawings wherein like characters denote like or corresponding parts throughout the sev- 25 eral views, and in which:—

Figure 1 is a view showing the invention in use.

Figure 2 is an elevation of the device.

Figure 3 is a perspective view thereof.

Figure 4 is a view of the slotted member.

Figure 5 is a view of the slide on the slotted member for adjusting the width of the slot therein.

Figure 6 is a view showing the device at- 35 tached to a support.

In these views, 1 indicates a member formed of a strip of metal or the like which is provided with an opening 2 and a slot or notch 3, the notch opening out through one 40 edge of the member, adjacent one end thereof. A hollow member 4 in the nature of a sleeve is slidably mounted on the member 1 and has a tongue or extension 5 at one end thereof which is bent over to engage one 45 side wall of the notch after the parts are assembled. This member acts to adjust the width of the slot 3 by moving the member 4 on the member 1. The upper surface of the extension 5 is provided with the parallel 50 grooves 6. The member 4 is also provided with an elongated opening 7 which registers with the opening 2. A knife 8 has its stem 9 provided with an elongated opening 10 which registers with the openings 2 and 7 so 55 that a bolt 11, provided with a wing nut 12, can be passed through the three members to

hold them together. The blade of the knife extends vertically by twisting the metal from which the knife is made in a quarter turn, so that the stem 9 will be flat, while the 60 blade is vertical. A portion of the knife will rest in one of the grooves 6, according to the adjustment of the knife on the other parts of the device, so that when the nut 12 is tightened, the knife will be held against 65 movement.

From the foregoing, it will be seen that the distance of the knife edge from the inner wall of the slot or notch 3 can be adjusted 70 so as to make the lacing to be formed of the desired width. By adjusting the member 4 on the member 1, the width of the slot or notch 3 can be adjusted to suit the thickness 75 of the piece from which the lacing is to be cut.

As shown in Figure 1, a hole is formed in the piece A and a tongue is cut from the inner edge of the piece. This tongue is forced through the inner portion of the notch or slot 3 so that it passes on the inner side of the knife with a portion of the piece A passing through the outer portion of the notch. Then by pulling the strip, the knife will cut a lacing from the same, as shown in 80 Figure 1. Of course, the piece must be turned so that the knife will pass in a circle around the inner edge of the same. It will also be understood that the device can be used for cutting lacings from the outer edges 85 of a piece of leather or the like by pulling the piece through the slot or notch 3 in such a manner that the knife will cut a lacing off the piece.

Figure 6 shows an arrangement for fas- 90 tening the device to a bench by the bolts 13 engaging base portions of the member 1.

It is thought from the foregoing descrip- 95 tion that the advantages and novel features of my invention will be readily apparent.

I desire it to be understood that I may 100 make changes in the construction and in the combination and arrangement of the several parts, provided that such changes fall within the scope of the appended claim.

What I claim is:—

A device of the class described including 110 a metal strip having a notch extending inwardly from one side thereof and provided with an opening intermediate its ends, a sleeve slidably mounted upon the metal strip, an extension at one end of the sleeve bent into U-shaped form for embracing one side

wall of the notch, said extension having parallel grooves in the upper face thereof, the sleeve having an elongated opening for registration with the opening in the strip 5 and a bolt extending through said openings to maintain the sleeve in various positions relative to the strip, a knife including a substantially flat stem formed with an elongated opening through which the bolt extends

whereby the stem may be adjusted relative 1 to the sleeve and strip and a knife blade formed on and disposed at right angles to the stem and adapted for engagement with the parallel grooves on the sleeve as and for the purpose specified

In testimony whereof I affix my signature.

GUSTAVE A. DOSTAL.
